C. FOSS.
SPIRAL PUMP.

Patented Aug. 4, 1832.

Cotton & Fife of Perry, County of Geauga, Ohio,
Letters Patent

The Schedule referred to in these Letters Patent and making part of
the same containing a description in the words of the said Cotton
& Fife, himself, of his improvement in the Pump called the Spiral Pump.

To all to whom these presents shall come, Cotton & Fife of Perry,
County of Geauga, and State of Ohio sends greeting.

Be it known that I the said Cotton & Fife, have invented and
applied to use a new and useful improvement in the pump called
the Spiral Pump, specified in the words following, viz.

This improvement consists of a round shaft, twenty inches in diam-
eter and 16 feet long with quadrangular points at its top & bottom
sufficiently large to support the pump, on this shaft a spiral
line is grooved out, extending from the top to the bottom of such
depth and width as shall get the edge of the shelf or floor, and is
to be ten feet between every winding spaces, or arms, three feet long
and eight inches long are placed in notches made in the said spi-
ral line. These arms are two inches square except where they enter
the shaft they are a little thicker. These arms are to project out
at right angles with the shaft and be of a convenient distance
apart and they will now form a winding or helical appearance.

The outside of the feet near the bottom of the shaft, is to be
shaped so as to resemble the root of an sugar and the upper sides of
the other arms are to be dressed off so as to correspond with the
inclination of the floor. Said floor is to be made of thin boards
cut out circularly so as to meet the roundness of the shaft and
the extremity of each arm. These boards are inserted in the spiral
groove before mentioned. Their ends meeting or breaking joints on
the upper side of the arms to which they are to be firmly fastened.
This floor will now form one continued line from one end to
the other of the shaft, and will project equally throughout the

upper side of the said floor must be perfectly smooth. A hoop one inch thick and two inches wide is placed on the outside edge of the floor as to be covered in, all round with thin boards or staves, nailed to the aforesaid hoop. over these is to be another layer, which is to cover the joints of the first layer, taking care that both the inner and outside boards shall fit as close, as possible so as to be water-tight. A hoop of suitable size is to be fastened on the outside of this covering in order to keep it in place. On the top is to be fixed a rim of suitable dimensions and placed at right angles with the shaft. The top of the shaft is to be elevated to three or four feet above the rim, so that a cog-wheel of bould construction may be attached to it. The gudgeon at the top of the shaft is to work in a beam, said beam to be fixed in the most convenient manner. To put this pump in operation the pivot at the bottom is placed in its support at the bottom of the well, and the gudgeon on top is fixed in the beam. Said beam being so adjusted as to give such an inclination to the shaft as shall allow the water to reach from the top of one rim to the bottom of the next above, allowing the upper pump to sink a little in the water as shown in the longitudinal section.

The pump is put in motion by suitable machinery acting on the bould wheel of the shaft and by the pump's construction of the floor, the water will be raised through the shaft until it falls over the rim on top, when it will be received into a trough or conductor from which it is applied to the purposes required.

These pumps may be made of wood, or any other kind of suitable materials, and the size may be diminished or increased or made of such dimensions as shall make it easily to be turned by hand. The principle of the pump I do not pretend to, but my claim consists in the improvement on the said principle, by the addition of the rim the pump can be made more perfectly without altering the nature of the boards and

will now know the quantity of water without the necessity of
doubting the power. I declare that the above is a true speci-
fication of my said improvement as above described. I have here set
my hand the first day of June one thousand eight hundred
and thirty two.
